(57) **CLAIM**

The ornamental design for a charging display stand for a mobile device, as shown and described.

DESCRIPTION

FIG. 1 is a front perspective view of a charging display stand for a mobile device.

FIG. 2 is a front view of the charging display stand.

FIG. 3 is a right side view of the charging display stand.

FIG. 4 is a rear view of the charging display stand.

FIG. 5 is a left side view of the charging display stand.

FIG. 6 is a top view of the charging display stand; and,

FIG. 7 is a bottom view of the charging display stand.

The broken lines represent environment that forms no part of the claim.

1 Claim, 3 Drawing Sheets
